MORRIS GELLER, OF NEWARK, NEW JERSEY.

DESIGN FOR A PHONOGRAPH-HORN.

No. 38,447.

Specification for Design.

Patented Feb. 19, 1907.

Application filed January 8, 1907. Serial No. 351,398. Term of patent 14 years.

To all whom it may concern:

Be it known that I, MORRIS GELLER, a subject of the Czar of Russia, residing at Newark, in the county of Essex and State of New Jersey, have invented a new, original, and ornamental Design for Phonograph-Horns, of which the following is a specification, reference being had to the accompanying drawings, forming part thereof.

Figure 1 is a side view of the phonograph-

horn, and Fig. 2 is an end view looking into the large end.

What I claim is—

The ornamental design for a phonograph-horn, as shown.

MORRIS GELLER.
